US00D981798S

(12) **United States Design Patent** (10) **Patent No.:** **US D981,798 S**
(45) **Date of Patent:** **** Mar. 28, 2023**

(54) **BEVERAGE CARRIER**

(71) Applicant: **Kimberly E. Nash**, New Lowell (CA)

(72) Inventor: **Kimberly E. Nash**, New Lowell (CA)

(**) Term: **15 Years**

(21) Appl. No.: **29/784,834**

(22) Filed: **May 21, 2021**

(51) **LOC (14) Cl.** **07-09**

(52) **U.S. Cl.**
